UNITED STATES PATENT OFFICE.

HENRY H. WAUGH, OF WHITMAN, MASSACHUSETTS, ASSIGNOR OF ONE-HALF TO CLARENCE D. REED, OF SAME PLACE.

MANUFACTURE OF BOOTS OR SHOES.

SPECIFICATION forming part of Letters Patent No. 352,899, dated November 16, 1886.

Application filed July 14, 1886. Serial No. 207,994. (No model.)

To all whom it may concern:

Be it known that I, HENRY H. WAUGH, of Whitman, county of Plymouth, and State of Massachusetts, have invented an Improvement in Boots or Shoes, of which the following description, in connection with the accompanying drawings, is a specification, like letters on the drawings representing like parts.

This invention has for its object to construct 10 a boot or shoe having a cork sole by an improved method, whereby the expense is materially decreased and a much better shoe produced.

In accordance with this invention an inter- 15 sole, or it may be a slip or tap sole, is provided on its upper surface with a thin piece or filling of cork of considerably less dimensions than the sole, and a piping-strip of leather, filled preferably with a cord, is secured by stitches 20 to the upper surface of the said intersole around the piece of cork. The intersole thus prepared is then placed upon the usual lasted shoe, and secured thereto by fastenings inserted through the intersole and the usual in- 25 ner sole, the said fastenings, preferably stitches, entering the intersole between the cork filling and the piping, the latter lying close to the outer edge of the upper, in the space between the upper and the intersole.

After this the outer sole is applied and secured to the intersole outside of the piping in 30 any usual manner, but preferably by stitches. Figure 1 shows in side elevation a Congress gaiter constructed in accordance with this 35 invention; Fig. 2, a cross-section of Fig. 1, taken on the dotted line *x* *x*; and Fig. 3, a plan view of the intersole, which is placed between the inner and outer soles of the boot or shoe.

The upper *a* is or may be of any usual construction, it being in this instance shown as shaped to produce a Congress gaiter, the upper being lasted over a last, *t*, having an inner sole, *b*, all in usual manner.

An intersole, *c*, (see Fig. 3,) shown as a full-length sole, (although it is obvious that, if desired, it may be merely a slip or tap sole,) has secured to its upper surface a thin piece of filling or layer of cork, *d*, which serves as a

filling-sole, as well as imparting the usual ad- 50 vantageous qualities of an ordinary cork sole. The cork layer *d* is of much less size than the surface of the intersole, to thus economize stock and give to the shoe the general appearance of a cork sole. A piping, composed preferably 55 of a folded strip of leather, *e*, surrounding a cord, *e*, is stitched or otherwise secured to the surface of the intersole around the piece or layer of cork *d*, and, as herein shown, the intersole *c* is of sufficient size to project some- 60 what, as at *f*, beyond the piping to serve the purpose of a welt.

The intersole *c*, prepared as above described, is placed upon the shoe after the upper has been lasted in usual manner, the cork layer *d* 65 lying contiguous to the inner sole, *b*. The intersole is then united to the lasted upper by a line of stitches or other suitable fastenings, 2, passed through the intersole, upper, and inner sole. The outer sole, *g*, is then applied to 70 the intersole *c*, and secured thereto by a line of stitches or other fastenings, as at 3, passing through the edge portion *f* of the intersole.

By the method herein described a shoe may be more cheaply put together than by any 75 method known to me, and a much better shoe produced.

I am aware that a shoe has been made containing an upper, inner sole, piping-cord, cork-filling sole, a welt, and an outer sole; 80 but in making the shoe the piping-cord was secured to the lasted shoe, and in order to hold the same in place a large number of tacks were employed, besides rendering the same liable to displacement when stitched.

If desired, the projecting edge *f* may be omitted, and the line of stitches or other fastenings 3, uniting the outer sole to the intersole, be made inside the outer edge of the piping.

It is obvious that the piping-strip of leather *e* may be filled with any other suitable material than cord, if desired.

I claim—

The herein-described method of manufacturing boots and shoes, which consists in lasting the upper to the inner sole, as usual, providing an intersole with a cork-filling sole,

and stitching to the intersole around the cork-filling sole a piping-cord, as described, securing the intersole thus provided with the piping-cord and cork-filling sole to the lasted 5 shoe, and, lastly, securing the outer sole to the intersole.

In testimony whereof I have signed my name

to this specification in the presence of two subscribing witnesses.

HENRY H. WAUGH.
